UNITED STATES PATENT OFFICE.

DANIEL WOODHEAD, OF CHICAGO, ILLINOIS.

DESIGN FOR A LIGHTING-FIXTURE.

47,677.

Specification for Design.

Patented Aug. 3, 1915.

Application filed May 25, 1914. Serial No. 840,954. Term of patent 3½ years.

To all whom it may concern:

Be it known that I, DANIEL WOODHEAD, a citizen of the United States of America, residing at Chicago, in the county of Cook and State of Illinois, have invented a new, original, and ornamental Design for a Lighting-Fixture, of which the following is a specification, reference being had to the accompanying drawing, forming part thereof.

The figure is an elevation of a car lighting fixture showing my new design.

I claim:

The ornamental design for a lighting fixture, as shown.

DANIEL WOODHEAD.
